F. J. ZOPPEL,

CONDENSER,

APPLICATION FILED DEC. 13, 1919.

1,391,989.

Patented Sept. 27, 1921.

UNITED STATES PATENT OFFICE.

FERDINAND JOSEPH ZOPPEL, OF CINCINNATI, OHIO.

CONDENSER.

1,391,989.

Specification of Letters Patent. Patented Sept. 27, 1921.

Application filed December 13, 1919. Serial No. 344,595.

To all whom it may concern:

Be it known that I, FERDINAND JOSEPH ZOPPEL, a citizen of the Republic of Austria, residing at Cincinnati, in the county of 5 Hamilton and State of Ohio, have invented new and useful Improvements in Condensers, of which the following is a specification.

My invention relates to refrigerating apparatus and particularly to the part known 10 as the condenser, and to its connective relation with other parts of the general system in which it is employed; being, in effect, an improved construction of the "condenser" in which is embodied an oil-separating 15 chamber and devices for oil separation. A cognate object, also, is to produce a construction at once simple and compact, with a view, (1), to construction and arrangement of parts, facilitating access to all requiring manipulation in construction and 20 use; (2), to the elimination of all avoidable jointings or connection of parts requiring packings and thereby possibilities of leakage; and (3) a structural arrangement enabling the assembly of the condenser with 25 other integral parts in a complete refrigerating apparatus at once compact in use, low cost of production, and greater efficiency in use.

With these general purposes certain minor 30 features of advantage are combined, as will further appear.

My invention is illustrated, in its preferred form, in the accompanying drawings 35 forming part of the specification following,—the several parts mentioned being designated by letters of reference.

In the drawings,—

Figure 1 is an elevation in axial cross section of the condenser and immediately associated connections; and

Fig. 2 a perspective elevation of the baffle-plate employed in the oil separation.

Referring now to the drawing herewith,— 45 in which the several parts are designated by digital numbers,—1, designates a hollow cylinder constituting the condensing chamber, closed at the top except as hereinafter specified and closed at the bottom by its seating upon the liquid-ammonia receiver, 2, of suitable form; and held tight by bolting through a bottom flange, 3, in connection with ordinary gaskets. Extending axially above and as part of the normal top of 50 the condenser, 1, is a short cylinder, 4, of

reduced diameter, closed at the top by a removable cover plate 5 from which depends a baffle-plate, 6, within the cylinder, 4.

The cylinder, 4, is extended, with slightly increased diameter, downward within and 60 to near the bottom of the cylinder, 1; and has a closed bottom, thus forming a receptacle for oil separated by the baffle-plate, 6.

The annular space within cylinder, 1, surrounding the lower extension of the cylinder, 4, is occupied by the pipe coil, 7, whose receiving and discharge terminals, 8 and 9, respectively, extend through the top and bottom of the chamber.

The upper or receiving pipe-terminal, 8, 70 connects as follows: A delivery pipe, 10, enters the side of the small cylinder, 4, facing the baffle-plate, 6. On the opposite side of the baffle and in line with the pipe 10 is a discharge pipe 11 which is connected by an 75 elbow-union, 12, with the intake pipe-terminal, 8. The outgoing terminal, 9, is carried downward through a union 13, and stop-valve, 14, and extension-pipe, 15, into the liquid-ammonia receiver, 2.

The condenser-cylinder, 1, carries, near the bottom, the condenser-water inlet-port, 16; and, near the top, the condenser-water outlet-port, 17, to maintain the necessary circulation.

The ammonia- and oil-vapor entering through the delivery pipe, 10, strikes directly against the baffle-plate, 6, which has a plane face with parallel corrugations extending vertically as indicated in Fig. 2. 90 It approximates in width the internal diameter of the cylinder, 4, so that the gas and vapor are compelled to pass downwardly around the bottom of the baffle plate. The oil-vapor, being heavy, clings to the baffle-plate and eventually drops into the bottom of the inner extension cylinder, 4.

Whenever desired, the oil can be withdrawn through a tube, 18, which extends from near the bottom of the cylinder-extension, 4, upward and outward through the cover plate, 5, stop-valve, 19, and discharge pipe, 20. Upon opening the stop-valve, 19, the pressure upon the oil level, α , will force the oil through the valve and outward 100 through the connecting pipe, 20.

The ammonia vapors, freed from oil, pass under the baffle-plate, 6, and out through the pipe, 11, and elbow, 12, into the coil, 7, of the condenser, from which it emerges in 110

condensed form through the outlet-terminal connection, 9, of the coil into the liquid receiver, 2.

It will be understood that in the ordinary 5 operation of the machine, the ammonia passes into the condenser under compression from a compressor (not shown) and by reduction of temperature and continued pressure is liquefied. The terminal, 9 of the condenser coil, 7, in passing through the extension plate 21 of the liquid ammonia receiver 10 2, is provided with screw nuts, 22, with intervening packing gaskets; and the terminal, 8, in passing through the top well of the 15 condenser is provided with an ordinary screw stuffing box 23 with packing gaskets.

I claim and desire to secure by Letters Patent of the United States:

1. In condensing apparatus, a condensing 20 chamber provided with an oil pocket having a closed bottom, said pocket embraced within and extending above the condensing chamber through an otherwise closed top, said chamber and pocket being formed as

a single integral structure provided with a 25 lower flange adapting it to rest upon and be secured to the ammonia receiver as a bottom support and closure.

2. In a condenser apparatus of the character indicated, in combination with the condenser cylinder and its central pocket, a removable top or cover for said central pocket, having a baffle-plate integral therewith and extending downward within said pocket. 30

3. In a condenser apparatus of the character indicated, a separator-pocket located and arranged in the condenser-chamber as described, and having a pressure-actuated outlet leading from the bottom of the separator-pocket, through its cover plate. 35

In testimony whereof I have hereunto set my hand in presence of two subscribing witnesses.

FERDINAND JOSEPH ZOPPEL.
